In Canada July 15, 1947

Term of patent 14 years

(Cl. D93—3)

To all whom it may concern:

Be it known that, we, Joseph Marcel Marisseau and Rosaire Duval, citizens of the Dominion of Canada, residing in the city of Montreal, Province of Quebec, Dominion of Canada, have invented a new, original, and ornamental Design for Band Saw, of which the following is a specification, reference being had to the accompanying drawings, forming part thereof.

Figure 1 is a perspective view showing the rear, top and one side of a band saw embodying our new design; and

Figure 2 is a perspective view showing the front, top and other side thereof.

The dominant features of our design reside in the portions shown in full lines.

We claim:

The ornamental design for a band saw, as shown and described.

JOSEPH MARCEL MARISSEAU.
ROSAIRE DUVAL.
